TILE

Stephan Eusemann, Nurnberg, Germany, assignor to
Dynamit Nobel Aktiengesellschaft

Filed June 13, 1972, Ser. No. 262,180

Claims priority, application Germany Dec. 13, 1971

Term of patent 14 years

Int. Cl. D25—01

U.S. Cl. D18—2 B

The figure is a top plan view of a basic component of a tile embodying my novel design;

The back of the tile as well as the sides are of conventional construction devoid of any ornamentation.

The drawing is shaded to show color contrast.

I claim:

The ornamental design for a tile, as shown and described.
